GOLF CART SERVICE TRAY

Casimir Waitekus, Pittsfield, Mass.

Application April 25, 1955, Serial No. 35,671

Term of patent 14 years

(Cl. D14—6)

I claim:
The ornamental design for a golf cart service tray, as shown.
